OIL WELL CAPPING DEVICE

William H. De Camp, Van Wert, Ohio

Application July 10, 1952, Serial No. 298,058

11 Claims. (Cl. 166—76)

1

The present invention relates to a capping device for oil and gas wells, and more particularly to a new and improved capping device having considerably more utility than prior art devices used heretofore.

Included in the many different kinds of oil and gas wells is the "gusher" which presents an appreciable number of problems and difficulties which, if circumvented, would materially reduce what is now considered normal wastage of oil and gas, and absolutely prevent the incalculable losses due to fire. In the drilling of a well, the final stage of drilling may be accompanied by an explosive eruption of oil and conglomerate from the well mouth which, in many cases, erupts with such violence and force that the heat of friction generated between well structures and the erupting fluids ignites the latter. When this occurs, the flow from the mouth of the well will continue to burn until the fire has been extinguished. Included in the fire-fighting techniques is the operation of covering the mouth of the well with a cap which shuts off the flow. As is well known to those skilled in the art, this operation of capping a well is extremely hazardous and time consuming in its accomplishment. Sometimes days and sometimes weeks pass before the capping of a well is completed. During this time, hundreds of barrels of oil are wasted and with present day knowledge that the world's oil supply is actually exhaustible, this costly wastage both from an economic and conservation standpoint, presents an acute and serious problem.

It is, therefore, an object of this invention, to provide an oil and gas well capping device which may be quickly and reliably operated to shut off the flow of a gushing well, and to thereby prevent any undue amount of wastage.

It is a further object of this invention to provide an oil and gas well capping device which may be operated from a point remote from the well thereby materially reducing the hazards connected with capping a well.

It is a still further object of this invention to provide an oil and gas well capping device which has utility in facilitating constant control of a gushing well, and to provide a mechanism which facilitates the actual construction of that portion of the well which extends above the ground.

Other objects and features of this invention will become apparent as the description proceeds.

To the accomplishment of the above and related objects, my invention may be embodied in the forms illustrated in the accompanying drawings, attention being called to the fact, how-

2

ever, that the drawings are illustrative only, and that specific change may be made in the specific constructions illustrated and described, so long as the scope of the appended claims is not violated.

In the drawings:

Fig. 1 is a perspective illustration of an embodiment of this invention;

Fig. 2 is a cross section of the embodiment of Fig. 1 taken through the valve portion thereof;

Fig. 3 is an axial section of the device of Fig. 1; and

Fig. 4 is a perspective view of a part of the construction of the preceding figures.

15 Referring now to the drawings, and more particularly to Fig. 4, the pipe or casing 10 represents that stub portion of the oil well which projects above the ground. The upper end of this casing 10 is threadedly received by a cylindrically shaped core 12, the threaded connection between this pipe 10 and core 12 being constituted by the threaded axial passage 14 extending entirely through the core 12. An upper casing member or pipe 16 is threaded into the upper end of the core 12, and carries on its upper end a hand valve 18 for controlling the flow of liquid from the nipple 20. As will be seen more clearly in Fig. 3, the passage 14 is threaded throughout its entire length for a purpose which will be explained more fully hereafter.

20 A rectangular opening 22 extends transversely through the core 12 and through the passage 14. For a purpose which will be explained more fully hereafter, the lateral extent of this opening 22 is equal to the diameter of the passage 14.

25 With the arrangement thus far described, it is possible to turn the upper pipe 16 downwardly until the lower end 18 (shown in dotted lines) extends below the opening 22 thereby severing communication between this opening 22 and the passage 14. The core 12 then becomes a pipe coupling or union joining the two pipe sections 10 and 16 together into a continuous fluid-conducting unit.

30 40 45 A valve housing or reinforcing encasement, generally indicated by the reference numeral 24, snugly surrounds the core 12, and for this purpose is provided with a cylindrical cavity 26 which conforms substantially to the exterior of the core 12.

45 50 55 As is seen more clearly in Figs. 1 and 2, this casing 24 is made in two sections 28 and 30 which are each provided with laterally projecting flanges 32 and 34, respectively, which are secured together by means of fastening members or bolts

36. The opposite ends of this casing 24 are provided with openings 38 and 40, respectively, for receiving therethrough the respective pipe sections 18 and 16. Section 38 of the casing is provided with a notch 42 in its inner surface for receiving the end of a valve plunger 44 which is reciprocably received within the opening 22 and another opening 46 extending transversely through the wall of casing section 28. As shown in Figs. 1, 2 and 3, plunger 44 completely severs communication between the lower and upper ends of the passage 14. This plunger 44 is so arranged that it may be retracted from its illustrated position to allow free communication entirely through the core 12.

A U-shaped, rigid support 48 is secured to casing section 28 by means of screws or the like 50 to extend radially outwardly from the casing 24. A lever 52 is received between the legs of the support 48 to be rockably mounted between its ends on the pivot pin 54. At a point spaced slightly above the pivot connection 54 is a pivot connection 56 between the plunger 44 and the lever 52. Two cables or the like 58 extend from the opposite ends of the lever 52 for rocking the lever about its pivot 54 which causes reciprocatory movement of the valve 44. Thus, by rotating the lever 52 counterclockwise, the valve 44 may be drawn to the left so as to open the passage 14.

A locking pin 60 passes transversely through casing section 28 and also through a transverse opening 62 in valve 44. On the left end of pin 60 may be received a nut or the like 63, or some locking arrangement which may be used to prevent tampering with the mechanism. With this pin in its illustrated position, the valve 44 is locked in closed position preventing communication between the ends of the passage 14. Upon removal of this pin, the valve 44 may be withdrawn by operating lever 52, and a different locking aperture 64 extending transversely through the plunger 44 may be brought into locked position by passing pin 60 therethrough. In this latter case the valve 44 would be locked in open position.

Another pin 66 received by an axially extending socket in casing section 28, which opens at the top of the casing, cooperates with a slot 68 in plunger 44 for limiting the extent of reciprocatory movement of the valve.

A typical use to which the present invention may be put is explained as follows. When in the drilling of a well it is decided that the drilling operation is substantially completed, the core 12 is screwed over the end of the protruding casing 10, and the upper section 16 is fitted into the core as shown in Fig. 4. The elbow and valve 19 are removed from the upper pipe section 16, and next, the outer casing 24 is mounted on the core 12.

Next, a charge of nitroglycerine is dropped through the upper pipe 16, the coupling 12, and into the casing 10. When this charge reaches the bottom of the well, it is exploded, and if a gas pocket or reservoir of oil under pressure is opened, a sudden rush or eruption of a mixture of oil, gas, rocks and other matter will blast out of the casing 10, up through the core 12, and out of the upper casing section 16.

Of course, when this blasting operation is taking place, the valve 44 is in its open position. When the well has fully cleaned itself of rocks and other foreign matter, and substantially pure oil or gas is rushing out, the lower cable 58 of

the lever 52 is pulled to force the plunger 44 inwardly through the valve opening 22 in core 12. This severs the flow of oil and gas from the well, and the well is then set to be capped.

5 If for some reason during this cleaning operation, or at any other time when oil or gas is flowing out of the pipe 16, a fire should occur, the only requirement to extinguish the fire, is to operate the lever 52 at a remote distance from 10 the well to force the plunger 44 inwardly to shut off the flow. The fire is thus effectively extinguished without the necessity of a worker risking his life to cap the well, and without the loss of any appreciable quantity of oil or gas.

15 When all fires have been extinguished, if there has been any, and the well has completely cleaned itself, the next step is to operate the lever to drive the valve 44 inwardly to shut off the flow. The hand valve 19 is now mounted on the upper 20 end of pipe section 16 and then closed.

Next, the plunger 44 is withdrawn from the passage 14, and the pipe section 16 is turned downwardly until its end 18 abuts against the upper end of casing 10. The core 12 now serves 25 as a union or coupling between the two pipe sections, and the casing 24 may be removed therefrom by means of the bolts 36.

From the foregoing, it will be apparent, that by the use of the present invention, flow of oil 30 from the well will be under complete control at all times, and when the capping and pipe fitting operations have been completed, it is seen that a part of the capping device may be effectively utilized as a section of the well structure itself. 35 With this arrangement, the core 12 is expendable and the casing 24 with its associated valve structure may be used again and again.

As explained previously, the present invention has particularly great and significant importance in the matter of both preserving life and property, and is therefore a meritorious contribution to the art.

What is claimed is:

1. An oil well capping device comprising a 45 cylindrical core having a threaded axial passage therethrough, a transverse opening provided through said core which intersects said passage, an outer casing comprised of two parts which may be detachably secured together and provided with a cylindrical cavity which is arranged to embrace snugly said core, threaded openings provided in the opposite ends of said casing in registry with said core passage, a transverse opening provided through one side of said casing and registering with the transverse core opening, the cavity wall of the other side of said casing having a notch which registers with said transverse core opening also, a valve plunger reciprocably received in said transverse 55 openings and said notch, a valve-operating lever pivotally connected to said plunger, a support carried by said casing and rockably mounting said lever between the ends of the latter, said lever being rockable to reciprocate said plunger into and out of said transverse core opening thereby providing valve control of fluid passing through said core passage, and two operating 60 connections on the ends of said lever whereby the latter may be operated from a remote distance, said core serving as a pipe coupling when said casing is removed therefrom.

2. An oil well capping device comprising a cylindrical core having a threaded passage therethrough, a transverse opening provided through 65 said core which intersects said passage, an outer

casing comprised of two parts which may be detachably secured together and provided with a cylindrical cavity which is arranged to embrace snugly said core, threaded openings provided in the opposite ends of said casing in registry with said core passage, a transverse opening provided through one side of said casing and registering with the transverse core opening, a valve plunger reciprocably received in said transverse openings, a valve-operating lever pivotally connected to said plunger, a support carried by said casing and rockably mounting said lever between the ends of the latter, said lever being rockable to reciprocate said plunger into and out of said transverse core opening thereby providing valve control of fluid passing through said core passage, and two operating connections on the ends of said lever whereby the latter may be operated from a remote distance, said core serving as a pipe coupling when said casing is removed therefrom.

3. An oil well capping device comprising a cylindrical core having a threaded passage therethrough, a transverse opening provided through said core which intersects said passage, an outer casing comprised of two parts which may be detachably secured together and provided with a cylindrical cavity which is arranged to embrace snugly said core, threaded openings provided in the opposite ends of said casing in registry with said core passage, a transverse opening provided through one side of said casing and registering with the transverse core opening, a valve plunger reciprocably received in said transverse openings, a valve-operating lever pivotally connected to said plunger, a support carried by said casing and rockably mounting said lever between the ends of the latter, said lever being rockable to reciprocate said plunger into and out of said transverse core opening thereby providing valve control of fluid passing through said core passage, and operating means mounted on said lever for operating the latter and said plunger, said core serving as a pipe coupling when said casing is removed therefrom.

4. An oil well capping device comprising a cylindrical core having a threaded axial passage therethrough, a transverse opening provided through said core which intersects said passage, an outer casing for said core and arranged to be separated therefrom, said casing being provided with a cylindrical cavity which is arranged to reinforcingly embrace said core, threaded openings provided in the opposite ends of said casing in registry with said core passage, a transverse opening provided through one side of said casing and registering with the transverse core opening, a valve plunger reciprocably received in said transverse openings, a valve-operating lever pivotally connected to said plunger, a support carried by said casing and rockably mounting said lever between the ends of the latter, said lever being rockable to reciprocate said plunger into and out of said transverse core opening thereby providing valve control of fluid passing through said core passage, and operating means mounted on said lever for operating the latter and said plunger, said core serving as a pipe coupling when said casing is removed therefrom.

5. An oil well capping device comprising a core element having a passage therethrough, an opening provided in said element which intersects said passage, said passage being threaded on both sides of said opening so that a pipe may be threaded through said intersection, a reinforcing casing re-

movably clamped onto said core element and having an opening through the wall thereof which registers with said first-mentioned opening, a valve member reciprocably received by both openings so that communication through said passage may be controlled, an operating lever operatively connected to said valve member, and a support on said casing which rockably supports said lever.

10 6. An oil well capping device comprising a core element having a passage therethrough, an opening provided in said element which intersects said passage, said passage being threaded on both sides of said opening so that a pipe may be threaded through said intersection, a reinforcing casing removably clamped onto said core element and having an opening through the wall thereof which registers with said first-mentioned opening, a valve member reciprocably received by both openings so that communication through said passage may be controlled, and operating means connected to said valve member for controlling opening and closing of said passage.

25 7. An oil well capping device comprising a core element having a passage therethrough, an opening provided in said element which intersects said passage, said passage being arranged to receive a pipe through said intersection for severing communication between said opening and said passage, a reinforcing casing removably clamped onto said core element and having an opening through the wall thereof which registers with said first-mentioned opening, a valve member reciprocably received by both openings so that communication through said passage may be controlled, and operating means connected to said valve member for controlling opening and closing of said passage.

30 8. An oil well capping device comprising a core element having a passage therethrough, an opening provided in said element which intersects said passage, said passage being threaded on both sides of said opening so that a pipe may be threaded through said intersection, a reinforcing casing removably clamped onto said core element and having an opening through the wall thereof which registers with said first-mentioned opening, a valve member received by both openings so that communication through said passage may be controlled, an operating lever operatively connected to said valve member, and a support on said casing which rockably supports said lever.

35 9. An oil well capping device comprising a core element having a passage therethrough, an opening provided in said element which intersects said passage, said passage being threaded on both sides of said opening so that a pipe may be threaded through said intersection, a reinforcing casing removably clamped onto said core element and having an opening through the wall thereof which registers with said first-mentioned opening, a valve member received by both openings so that communication through said passage may be controlled, and operating means connected to said valve member for controlling opening and closing of said passage.

40 10. An oil well capping device comprising a core element having a passage therethrough, an opening provided in said element which intersects said passage, said passage being arranged to receive a pipe through said intersection for severing communication between said opening and said passage, a reinforcing casing removably clamped onto said core element and having an opening through the wall thereof which registers

with said first-mentioned opening, a valve member received by both openings so that communication through said passage may be controlled, and operating means connected to said valve member for controlling opening and closing of said passage.

11. An oil well capping device comprising a core element having a passage therethrough, an opening provided in said element which intersects said passage, said passage being arranged to receive a pipe through said intersection for severing communication between said opening and said passage, a reinforcing casing removably

clamped onto said core element and having an opening through the wall thereof which registers with said first-mentioned opening, and valve means operatively received by both openings for controlling communication through said passage.
